COMBINATION LETTER OPENER AND DIALER

Cleone L. Kahn, Cleveland, Ohio

Application June 2, 1949, Serial No. 3,010

Term of patent 7 years

(Cl. D74—1)

To all whom it may concern:

Be it known that I, Cleone L. Kahn, a citizen of the United States and residing at Cleveland, in the county of Cuyahoga and State of Ohio, have invented a new, original, and ornamental Design for a Combination Letter Opener and Dialer, of which the following is a specification, reference being had to the accompanying drawings, forming a part thereof

In the drawings:

Fig. 1 is a front elevational view of a combination letter opener and dialer showing my new design;

Fig. 2 is a side elevational view thereof;

Fig. 3 is a top plan view thereof;

Fig. 4 is a horizontal sectional view thereof taken on the line 4—4 of Fig. 1;

Fig. 5 is a horizontal sectional view thereof taken along the line 5—5 of Fig. 1.

I claim:

The ornamental design for a combination letter opener and dialer, substantially as shown.

CLEONE L. KAHN.
